(57) **CLAIM**

The ornamental design for a crossfit gymnastics grip, substantially as shown and described.

DESCRIPTION

FIG. 1 is a perspective view of an open configuration of my crossfit gymnastics grip.

FIG. 2 is a front view of the configuration of FIG. 1.

FIG. 3 is a back view of the configuration of FIG. 1.

FIG. 4 is a left side view of the configuration of FIG. 1.

FIG. 5 is a right side view of the configuration of FIG. 1.

FIG. 6 is a top view of the configuration of FIG. 1.

FIG. 7 is a bottom view of the configuration of FIG. 1.

FIG. 8 is a perspective view of a closed configuration of my crossfit gymnastics grip.

FIG. 9 is a front view of the configuration of FIG. 8.

FIG. 10 is a back view of the configuration of FIG. 8.

FIG. 11 is a left side view of the configuration of FIG. 8.

FIG. 12 is a right side view of the configuration of FIG. 8.

FIG. 13 is a top view of the configuration of FIG. 8; and,

FIG. 14 is a bottom view of the configuration of FIG. 8.

The dotted dash lines shown in the figures are for the purpose of showing stitching which form part of the claimed design.

1 Claim, 7 Drawing Sheets
